UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed March 8, 1921. Serial No. 450,735.

To all whom it may concern:

Be it known that I, FRED S. CARR, a citizen of the United States, and a resident of Newton, in the county of Middlesex, Commonwealth of Massachusetts, have invented an Improvement in Separable Fasteners, of which the following description, in connection with the accompanying drawings, is a specification, like characters on the drawings 10 representing like parts.

This invention pertains to improvements in separable fasteners. It is among the objects of the invention to provide a superior snap fastener of simple and inexpensive construction.

In the drawings, which show a preferred form of one embodiment of my invention:—

Figure 1 is a front view of a preferred form of fastener, the stud and socket being 20 secured to flexible carrying means which are shown partially broken away;

Fig. 2 is a section on the line 2—2 of Fig. 1, being partly in elevation; and

Fig. 3 is an enlarged section through the 25 socket and stud of the fastener on the line 3—3 of Fig. 2.

Referring to the drawings and to the preferred form of fastener selected for illustrative purposes, I have shown a stud having a 30 head 4 and a shank or neck 5, which may be secured to the stud-carrying fabric 6 in any suitable way, but preferably, as shown, by a metallic securing element 7, into which the base 8 of the stud may be expanded, as shown 35 in my co-pending application Serial No. 331,780, filed January 16, 1920, to press the material into the securing element 7 beneath the flange 9 thereof. The socket may include a casing 10 secured to the socket-carrying fabric 11 in any suitable way, but preferably, as 40 illustrated, by expanding projections 12 from the socket casing 10 behind a rim 13 of a socket-securing cap 14, the fabric 11 being pressed into and held in the socket-securing 45 cap, preferably without perforation of the fabric. To minimize the chances of tearing or penetrating the fabric, the ends 15 of the projections 12 may be rolled over as shown, thereby to present a blunt edge to the fabric.

50 The socket-securing cap 14 is preferably provided with an anvil surface 16 which guides the socket-securing projections outwardly during the socket-securing operation. In the preferred form of my invention selected 55 for illustrative purposes, the socket 10 con-

tains a spring 20 which is preferably, as shown, a flat metal disc having a stud-receiving aperture therethrough and split at one side, as shown at 21, to permit the disc to act as a spring, sufficient expansion being 60 provided to permit the head of the stud to enter the socket.

The preferred form of fastener illustrated is preferably adapted to be locked against undesired separation of stud and socket by 65 reason of the resolution of forces arising from lateral strains. This locking is preferably effected by notches 22 in the exterior periphery of the spring 20 at each side of the split 21. Projections 23 enter the notches 70 22, these projections 23 being preferably a part of the socket casing. The projections 23 are preferably so located as to enter the notches 22 somewhat at all times, thereby preventing any substantial turning movement of the spring 20 in the casing 10. The fastener should be applied to the carrying medium with the notches 22 in the line of strain so that as the stud tends to move to the right, as viewed in Fig. 3, and the socket 75 casing to the left, the spring 20 will move to the right relative to the casing 10, thereby causing the projections 23 to engage in the notches 22 and prevent expansion of the spring to release the head of the stud. 80

In the preferred form of my invention selected for illustrative purposes, the projections 23 are thrown inwardly from the periphery of the socket casing and are wedge-shaped, the portions thereof most closely adjacent the split 21 being the portions which hold the spring closed under lateral strain and the other portions thereof serving as struts to back up and strengthen the first mentioned portions thereof which 95 receive the direct pressure from the spring.

While I have shown and described a preferred form of one embodiment of my invention, it will be understood that major changes involving omission, substitution, alteration and reversal of parts, and even changes in the mode of operation, may be made without departing from the scope of my invention, which is best defined in the following claims.

Claims.

1. A separable fastener comprising, in combination, a stud having a head and a neck, a socket including a casing, a spring loosely fitting said casing laterally, to per-

mit shifting of said spring in said casing laterally, a stud-receiving aperture in said spring, a split from said stud-receiving aperture to the periphery of said spring, projections on said spring at each side of said split, and abutments from the casing for engagement at each side of said projections when strain is exerted tending to move said spring in said casing in a direction toward the split in the spring, said projections and said abutments opposing stud-releasing opening of said spring when in contact with each other.

2. A separable fastener comprising in combination, a stud having a head and a neck, a socket including a casing, a spring loosely fitting said casing laterally, to permit shifting of said spring in said casing laterally, a stud-receiving aperture in said spring, a split from said stud-receiving aperture to the periphery of said spring, projections on said spring at each side of said split, and abutments from the casing for engagement at each side of said projections when strain is exerted tending to move said spring in said casing in a direction toward the split in the spring, said projections and said abutments opposing stud-releasing opening of said spring when in contact with each other, said abutments cooperating with said projections to prevent substantial turning movement of said spring relative to said casing.

3. A separable fastener comprising, in combination, a stud having a head and a neck, and a socket including a casing having a spring therein providing a stud-receiving aperture and a split from said aperture to the periphery of the spring, two

notches in the spring, one at each side of said split, and wedge-shaped projections from the periphery of the casing extending into said notches, said projections providing clearance to permit expansion of said spring when stud and socket are not under lateral strain urging said notches toward said projections, and said projections engaging the faces of said notches adjacent said split when strain is exerted between stud and socket to urge said spring toward said projections.

4. A separable fastener comprising, in combination, a stud having a head and a neck, and a socket including a casing having a spring therein providing a stud-receiving aperture and a split from said aperture to the periphery of the spring, two notches in the spring, one at each side of said split, and wedge-shaped projections from the periphery of the casing extending into said notches, said projections providing clearance to permit expansion of said spring when stud and socket are not under lateral strain urging said notches toward said projections, and said projections engaging the faces of said notches adjacent said split when strain is exerted between stud and socket to urge said spring toward said projections, the portions of said projections adjacent said split providing cam surfaces and the portions of said projections furthest removed from said split providing supporting struts for strengthening the first-named portions of said projections.

In testimony whereof, I have signed my name of this specification.

FRED S. CARR.
